SYNCHRONIZING SYSTEM

Application filed December 24, 1931. Serial No. 583,002.

My invention relates to phase correction of two remotely disposed rotating members, and more particularly to synchronous telegraph or signalling systems.

5 The object of my invention is to provide simple and efficient means for keeping the remotely disposed members in phase with each other.

10 Telegraph systems such as that herein illustrated and described comprise rotating distributors remotely disposed with respect to each other and connected by a signalling conductor in which is disposed a polarized relay responsive to signals from the transmitting station. Systems of this type have 15 distributors which operate at slightly different speeds, one of the distributors, usually that at the receiving station, being periodically corrected to synchronism with the other. The signals transmitted are composed of spacing or positive impulses and 20 marking or negative impulses.

25 The corrector mechanism comprises control relays initially controlled by the operation of the polarized relay when responding to the received impulses. These control relays are then controlled in sequence by cams associated with the distributor mechanism.

30 The co-operation between the control relays and the cams eliminates the so-called "dead spot" so correction can take place at any period during the rotation of the distributor.

35 Other objects of my invention will be pointed out in the description to follow.

Referring to the drawing:

40 A drive shaft 45 for the distributor driven by means not shown carries a fly wheel 50 and a freely rotating brush carrier 47. The brush carrier has a gear wheel 48 formed integral therewith, which meshes with a pinion 39 secured to a short shaft 40 which is journaled in a control disc 41 operatively secured to shaft 45 by any suitable means 45 such as pin 42. The other end of the shaft 40 has a star wheel 46 secured thereto which is prevented from rotating by a spring actuated detent roller 49 carried by control disc 41. Mounted upon the shaft 45 and 50 rotatable therewith are two cam discs C1

and C2, the former controlling contacts 12 and 13 and the latter controlling contacts 22 and 23.

A polarized line relay is shown at 2. The tongue of relay 2 follows the received 55 line signals. When the tongue of relay 2 is resting against its spacing contact S, the condenser 3 will be discharged through resistance 4. When a marking signal is received, the tongue of relay 2 will move over to the marking contact M and the condenser 3 will be charged from battery 5. The charging current for condenser 3 will flow through windings of locking relay 6. If the brush 7 is in proper phase relation with 60 the received signals, then brush 7 will be on the B segments at the instant the tongue of relay 2 arrives at its marking contact, and the charging circuit of condenser 3 will be 65 as follows: from battery 5, through condenser 3, marking contact M, windings 8 and 9 of relay 6, segment B, brush 7, and thence through solid ring 10 to ground. It 70 should be noted that the charging impulse goes through windings 8 and 9 in series and that these windings are connected in opposition. Since windings 8 and 9 have an equal number of turns, it will be apparent 75 that the armature 11 of relay 6 will not be operated. The resistance of windings 8 and 9, however, limits the charging current 80 of condenser 3 and thereby prevents damage to the contacts of relay 2 or the distributor segments and brushes. When the brush 7 is out of phase with the received signal, the 85 brush will be on the A segment at the instant that the tongue of relay 2 arrives at its marking contact.

The path of the charging impulse of condenser 3 will be as follows: from battery 5, 90 through condenser 3, contact M, winding 8 of relay 6, segment A, brush 7, solid ring 10, and thence to ground. Since the charging current, in this case, passes through only one winding of locking relay 6, the armature 11 will be attracted and the relay will 95 lock up.

Let us assume an out of phase condition occurs when the distributor is in the position shown, and the impulse from relay 2 100

tends to operate locking relay 6. A locking circuit will be completed from positive battery 28, tongue 31, contact 30, winding 11 to ground through either of two circuits; one of these circuits is through the contacts 22 and 23 of cam C2, the other circuit through the contacts 25 and 19 of differential relay 27. Relay 27 and corrector magnet CM will not at present be operated. Later on in the revolution of the distributor, cam C1 will operate its contacts and complete a circuit from ground, through contacts 12 and 13, contact 14, tongue 15, winding 16 of relay 27, and to positive battery. There will be no circuit through winding 17 since relay 6 is locked up and, therefore, relay 27 will operate. Tongue 15 of relay 27 is arranged so that it will touch its front contact 18 before it leaves its back contact 14, and will lock itself up through its front contact 18. When relay 27 operated its right hand tongue 19 closed a circuit from ground, through front contact 20, winding of corrector magnet CM and battery 21 to ground, thus energizing the corrector magnet which, in turn, places pin 13 in the path of the star wheel 46, which thus effects the correction. Shortly after the correction is made cam C2 will open its contacts 22 and 23, thereby de-energizing locking winding 11 of relay 6, and that relay will fall back to its normal position. Later on in the revolution of the distributor, cam C1 will close contacts 12 and 13 and current will flow through winding 17 of relay 27, and this winding will neutralize the locking winding 16 and, therefore, the armatures of this relay will fall back to their unoperated positions. As long as contacts 12 and 13 are closed and the tongue 31 of locking relay 6 is restored to its back contact 24, the currents in windings 16 and 17 will neutralize each other. It will be apparent that the moment at which relay 27 is operated and unoperated is determined by the closure of contacts 12 and 13, which are controlled by cam C1. Corrector magnet CM, therefore, will be energized for a complete revolution of the distributor. It will be noticed that a circuit to ground from winding 11 of relay 6 can be made through contacts 22 and 23, and also through contact 25 and tongue 19 of relay 27. The purpose of having this additional path to ground through the contacts of relay 27 is to prevent the relay 6 from becoming unresponsive to correcting impulses. If, for example, a correcting impulse should occur during the instant cam C2 has opened contacts 22 and 23, the locking relay 6 will be able to lock itself up through the contacts of relay 27. If the distributor is out of phase a considerable amount, and a correction is required on two or more successive revolutions, then the differential relay 27 and corrector magnet CM

will remain continuously operated during the several revolutions of the distributor. It has been previously mentioned that the cams C1 and C2 are disposed on the shaft so that cam C1 operates its contacts, and shortly after this cam C2 operates its contacts. This occurs every revolution. In this circuit it is not possible for correction to occur on two successive revolutions if the correcting impulses happen to occur during the brief interval which elapses between the time cams C1 and C2 operate their contacts. The following will describe the operation of this circuit when two successive correction impulses occur on two successive revolutions shortly after cam C1 has operated its contacts, but before cam C2 has operated its contacts. When cam C1 closes contacts 12 and 13 relays 6 and 27 are in the unoperated position, as shown, and current will flow through windings 16 and 17 of relay 27, and since these two windings neutralize each other relay 27 will be unoperated. Assume now that the condenser discharge from the impulse relay 2 now tends to operate relay 6. Relay 6 will lock itself up through the following circuit: battery 28, tongue 31, contact 30, locking winding 11, contact 25, and tongue 19 to ground. Cam C2 will now open its contacts 22 and 23 momentarily, but this will not unlock relay 6 since this locking circuit is maintained through contacts 25 and tongue 19. Cam C1 now closes contacts 12 and 13 and current now flows through winding 16 only, of relay 27. Relay 27 operates and locks itself up through its tongue 15 and contact 18. The operation of relay 27 in turn energizes corrector magnet CM, and the pin 5 will engage with star wheel 6 and correct the distributor. Now assume that the discharge from impulse of relay 2 again tends to operate locking relay 6. Locking relay 6 is already locked up and, therefore, this correcting impulse has no effect on it. When the cam C2 again opens its contacts 22 and 23, locking relay 6 will be de-energized since it does not now have the alternative circuit through contact 25 and tongue 19. When the cam C1 again closes its contacts 12 and 13, differential relay 27 will be de-energized, and this in turn will de-energize corrector magnet CM. There is a distinct advantage in having double corrections prevented during the interval between the operation of cams C1 and C2, because many of the correcting impulses which tend to operate relay 6 at that time are false. The reason for this is, that it takes a short time for the mechanical displacement between the brushes and the driving member of the distributor to occur, and if this shifting action has been initiated but not completed, the distributor will be apparently out of phase although it is at the time be-

ing brought into phase. By suitably positioning cams C1 and C2 with respect to the engagement of star wheel 6 with correcting pins 5 it is possible to eliminate 5 these unnecessary double corrections.

From the above description it will be apparent that this invention eliminates the 10 tendency for unnecessary double corrections to occur and, furthermore, it eliminates the so-called "dead-spot" or position in which the circuit is unresponsive to the correcting impulse.

What is claimed is:

1. In a periodically synchronized telegraph system, the combination of a distributor comprising a rotating contactor and driving means therefor, a corrector magnet for adjusting the angular displacement of said contactor in relation to said 20 driving means, means for conditioning said corrector magnet for operation at any time in a revolution of said driving means, and means for operating said corrector magnet at a fixed point in a revolution of said driving 25 means.

2. A system for phasing two remotely located rotating bodies comprising driving means for each of said bodies, one of said driving means operating at a greater speed 30 than the other, means for transmitting signals at a speed proportional to said slower driving means speed, a corrector magnet conditioned for operation whenever said rotating bodies are a predetermined amount 35 out of phase, a cam for causing operation of said corrector magnet at a fixed point in the cycle of said faster driving means, and mechanical means operated by said corrector magnet to cause retardation of said 40 faster rotating body in respect to its driving means.

3. In a periodically synchronized telegraph system, the combination of a rotating distributor, a phase correcting mechanism 45 therefor, means for operating said correcting mechanism at a fixed point in a distributor revolution, means for maintaining said correcting mechanism operated during a complete revolution of said distributor, and 50 mechanical means for initiating correction of said distributor during said revolution.

4. In a telegraph system, the combination of a periodically phased rotating distributor, a corrector mechanism therefor, means 55 for operating said corrector mechanism at a fixed point in a distributor revolution, means for normally maintaining said corrector mechanism operable during a complete revolution of said distributor, mechanical means 60 for initiating correction of said distributor during said revolution, said mechanical means possessing inherent lag, and means for preventing said corrector mechanism from again operating prior to the rotation 65 of said distributor to another fixed point de-

termined in accordance with the amount of said lag.

5. In a telegraph system, in combination with a distributor comprising rotating brushes adapted to be phase corrected, a corrector magnet, means comprising a cam and contacts operable thereby to cause energization of said corrector magnet and subsequent de-energization of said corrector magnet after said brushes have been phase corrected, and circuit means for causing re-energization of said corrector magnet when said period of energization is insufficient to effect necessary correction. 70

6. A phase correction system for telegraph systems, comprising a distributor having rotating brushes and a driving means therefor, a differential relay operable when correction is needed, a second differential relay conditioned for operation by 80 said first relay, cam controlled means operable at a fixed point in a rotation of said driving means to operate said second relay, a corrector magnet operated by said second relay to effect correction of said brushes in 85 respect to said driving means, circuit means operable to maintain said second relay operated for a complete revolution of said driving means, and a second cam controlled means operable at a second fixed point in 90 said distributor cycle to effect de-energization of said first relay. 95

7. A phase correction system for telegraph systems, comprising a distributor having rotating brushes and a driving means therefor, a differential relay operable when correction is needed, a second differential relay conditioned for operation by 100 said first relay, cam controlled means operable at a fixed point in a rotation of said driving means to operate said second relay, a corrector magnet operated by said second relay to effect correction of said brushes in respect to said driving means, a second cam controlled means operable at a second fixed point in 105 said distributor cycle to effect de-energization of said first relay, means comprising said first cam to normally de-energize said second relay and corrector magnet 110 after a complete revolution of said driving means, and a circuit connection between said first and second relays to prevent de-energization of said first relay at said second fixed point and consequently de-energization of said second relay at the completion 115 of a revolution when further correction is necessary. 120

8. A phase correction system for telegraph systems comprising a distributor having rotating brushes and a driving means therefor, a differential means operable when correction is needed, a corrector magnet conditioned for operation by operation of said relay, cam controlled means operable at a 125 fixed point in a rotation of said driving 130

means to operate said magnet to effect correction of said brushes in respect to said driving means and upon the succeeding operation thereof to effect de-energization of said corrector magnet, a second cam controlled means operable at a second fixed point in said distributor cycle to effect de-energization of the relay in the event that the corrector magnet is at that time operated, and circuit means effective when said relay operates in that portion of the distributor cycle lying between said first and said second cam controlled means to maintain said relay operated until the second operation of said second cam controlled means following the said operation of said relay.

In witness whereof, I hereunto subscribe my name this 23rd day of December 1931.
